UNITED STATES PATENT OFFICE

2,558,173

COLLAPSIBLE HEATER SUPPORT FOR
RAILROAD CAR BUNKERSNehman R. Duff and Harry H. Hutchison,
Blue Island, Ill.

Application February 27, 1948, Serial No. 11,806

2 Claims. (Cl. 105—355)

1

Our invention relates to heater supports, particularly those in connection with the heating of freight cars, this invention being an improvement on our co-pending patent application, designated Serial Number 748,362 filed May 15, 1947.

An object of our invention is to provide a heater support that may be quickly mounted on one of the bunker walls of a box-car type of freight car without remodeling or changing thereof.

A further object of our invention is to provide a heater support, of the above-mentioned character, having a heater supporting assembly that is collapsible within the attaching frame which is mounted on the wall of the bunker.

A still further object of our invention is to provide a heater support assembly that may be quickly and easily opened to rest upon a ledge in the side of the said bunker.

A further object of our invention is to provide a heater support assembly, the sides and end walls of which may be quickly and easily raised to their open position and securely latched to form a support for a box-car heater.

A still further object of our invention is to provide a spring-urged locating pin means to hold the said side frames, in their upward position, while raising the end frames to a latching position thereto.

A further object of our invention is to provide a latching means for securely holding the heater support, in its collapsed position, within the supporting frame attached to the bunker wall when not in use.

Other objects and advantages embraced in our invention will be disclosed in the following description and the accompanying illustrations, in which like parts are designated by like numerals, and in which:

Fig. 1 is a front view of our heater support shown mounted upon the wall of a box-car bunker.

Fig. 2 is a perspective view of our heater support, with the heater-holding assembly folded down and resting upon its supporting ledge.

Fig. 3 is a perspective view of our heater support showing the side frames of the heater-holding assembly raised and the end frames being swung into position.

Fig. 4 is a perspective view of our heater support shown in operating position, and with a car heater shown in phantom lines therein.

Fig. 5 is an enlarged cross-sectional view of a fragment of our invention taken substantially on line 5—5 on Fig. 1.

2

Fig. 6 is an enlarged fragmentary, cross-sectional view of our invention taken substantially on line 6—6 on Fig. 1.

Referring to the illustrations, our invention is generally designated as 7, and consists of an attaching frame 8, preferably made of lengths of angle iron welded together and forming a rectangular shape. The said attaching frame 8 is secured by bolts and nuts 9 to one of the inside bunker walls 10 of a box-car bunker 11. The said bunkers are usually located at each end of the box-car type of freight car 11.

A heater supporting assembly 12 consists of a heater supporting base frame 13, one end of which is pivotably attached by pivot rod 14 to the lower end of attaching frame 8. The said heater supporting base frame 13 is of a size to allow it to collapse and fit within the attaching frame 8 when not in use, as shown in Fig. 1. When 15 opened downwardly to an operative position, the said heater supporting base frame 13 rests upon a supporting ledge 15 on the opposite inside bunker wall 16. Two side frames 18 and two end frames 19 are preferably made of welded strap iron, and are of a size to fit between two angle iron sides of the heater supporting base frame 13. The said side frames 18 and end frames 19 are provided with bearings 20 and 21, respectively, on their lower or attaching ends.

Swivel rods 22 provide the means for connecting the bearings 20 and 21 of the said side frames 18 and end frames 19 to side support bearings 23 and end support bearings 24, which are mounted upon the base supporting frame 13.

It will be noted from the various views, and Fig. 5 in particular, that the side support bearings 23 are mounted in different planes than the end support bearings 24. This provides the means for allowing the side frames 18 and end frames 19 to lie in a collapsed position, flush with the heater supporting base frame 13, as shown in Fig. 2. The side support bearings 23 are counterbored at 25, as shown in Fig. 5, and the said counterbores are provided with reduced openings 26, through which a locating pin 29 extends. The head 28 of the locating pin 29 is held in position, within the counterbore 25, by the shoulder 27, and the pin 29 is maintained, in extended position, by spring means 30 within the said counterbore 25 enclosed by a screw plug 31 in the tapped counterbore mouth 32.

The side frames 18 are provided with latches 33, one at each end near the top, as shown in Figs. 3 and 4. The said latches 33 are pivoted at 34 to latch braces 35, which are welded to the said side frames 18. Limiting pins 36 and 56 are

mounted on the said latch braces 35, beneath the latches 33, to maintain the said latches in position to engage the aligned locking slots 37 which are formed in end frames 19.

In the closed position, as illustrated in Fig. 1, the heater supporting assembly 12 fits within the attaching frame 8 and is held thereby a locking latch 41. The said locking latch 41 is pivotably attached through holes 43 and 44 through attaching frame 8 and locking latch 41 by means of attaching bolt 42 and hand knob 45. The said hand knob 45 is counterbored at 46 and provided with a reduced opening 47 through which the reduced threaded end 48 of attaching bolt 42 extends. A lock nut 49 holds the said hand knob 45 in place. The attaching bolt 42 should be slightly longer than the combined thicknesses of the supporting frame 8 and locking latch 41 plus the depth of counterbore 46 to prevent binding of the said locking latch 41 when the lock nut 49 is tightened on the reduced threaded end 48.

An engaging pin 52 provides engaging relationship between the hand knob 45 and the locking latch 41 by means of counterbored holes 53 in said hand knob 45 and locking latch 41, as shown in Fig. 6. Locking latch 41 may be provided with a boss 51 to relieve the remaining surface thereof from frictional contact with frame 8. A spring 50 within counterbore 46 by bearing against the locking latch 41 provides the said frictional pivoting action between locking latch 41 and the attaching frame 8, so that the said locking latch will remain in an inoperative position while the heater assembly 12 is down.

When the heater supporting assembly 12 is lowered by means of a hook 54 to its resting position on supporting ledge 15, the two side walls 18 may be raised to an upright position, as shown in Fig. 3, and are maintained in that position by the locating pins 29 resting in dimples 55, formed in the heater supporting base frame 8, as shown in Fig. 5. The two end frames 19 are then swung upwardly and outwardly, as shown in Fig. 3, and are latched against the ends of side frames 18 by means of the ears 38 passing through the slots 37 therein. The heater supporting assembly 12 is now locked, in an operable position, so that a heater, designated 39 and shown in phantom lines in Fig. 4, may be placed therein to rest upon heater support struts 40, welded into the heater supporting frame 13.

Our heater support may preferably be mounted upon the wall of one of the end bunkers of a freight car and within reaching distance of the overhead hatch so that the said car heater may be serviced from above, without the necessity of a man climbing into the bunker. This is a great advantage over the present practice in which car heaters are placed on the floor of the bunker, thus requiring two men to service the said heater as required by law if and when one man had to climb into a heating bunker.

Although we have herein described rather succinctly the nature and use of our invention so that persons skilled in the art will have no difficulty apprising themselves of the teachings thereof and, inasmuch as the disclosure is susceptible of various alterations, modifications, and improvements, we hereby reserve the right to all modifications, alterations, and improvements falling within the scope and spirit of our invention, as well as any modifications that are embraced suggestively in the accompanying draw-

ings, and any that may come within the purview of the foregoing description; our invention to be limited only by the appended claims.

Having thus described and disclosed our invention, what we claim as new, and desire to secure by Letters Patent, is:

1. Heater support means for the bunker of a freight car comprising, an attaching frame attachable to a wall of said bunker, a collapsible and erectable heater supporting assembly articulately secured to one end of the said attaching frame and constructed and arranged to fit within the confines of the said attaching frame when the said heater supporting assembly is collapsed, locking means on the end of the said attaching frame which is in opposed relationship to the said first-mentioned end of the said attaching frame, and a supporting ledge on a wall of the said bunker in opposed relationship to the said first-mentioned wall, the said collapsible and erectable heater supporting assembly including, a heater supporting base frame, two side frames and two end frames hingedly secured to the said base frame in overlapping relationship when collapsed, and constructed and arranged to be erected to form a four-sided enclosure, and spring-urged locating pin means secured to the bottom edges of the said side frames for releasably maintaining the same in an upright position to facilitate erection of the said enclosure.

2. Heater support means for the bunker of a freight car comprising, an attaching frame attachable to a wall of said bunker, a collapsible and erectable heater supporting assembly articulately secured to one end of the said attaching frame and constructed and arranged to fit within the confines of the said attaching frame when the said heater supporting assembly is collapsed, locking means on the end of the said attaching frame which is in opposed relationship to the said first-mentioned end of the said attaching frame, and a supporting ledge on a wall of the said bunker in opposed relationship to the said first-mentioned wall, the said collapsible and erectable heater supporting assembly including, a heater supporting base frame, two side frames and two end frames hingedly secured to the said base frame in overlapping relationship when collapsed, and constructed and arranged to be erected to form a four-sided enclosure, and spring-urged locating pin means secured to the bottom edges of the said side frames for releasably maintaining the same in an upright position to facilitate erection of the said enclosure.

NEHMAN R. DUFF.
HARRY H. HUTCHISON.
